UNITED STATES PATENT OFFICE.

WILLIAM H. ADKINS, OF KANSAS CITY, KANSAS.

AUTOMATIC TRAIN-STOPPING, TELEPHONIC, AND BLOCK-SIGNAL SYSTEM.

1,400,201.

Specification of Letters Patent.

Patented Dec. 13, 1921.

Application filed August 14, 1917. Serial No. 186,244.

To all whom it may concern:

Be it known that I, WILLIAM H. ADKINS, a citizen of the United States, residing at Kansas City, in the county of Wyandotte 5 and State of Kansas, have invented certain new and useful Improvements in Automatic Train-Stopping, Telephonic, and Block-Signal Systems, of which the following is a specification.

10 My invention relates to an automatic train stopping, telephonic and block signal system, and one object is to provide a simple, reliable, easily operated, electrical system of this character which can be easily installed 15 and operated in connection with the standard forms of tracks and lines of both steam and electric roads, and whereby two trains may be placed in telephonic connection with each other or with despatchers along the 20 right of way.

A further object is the provision of signal means to warn an approaching train of an open switch or derail, so that such train may be stopped within a safe distance before 25 taking the switch or siding.

With the foregoing and other objects in view which will appear as the description proceeds, the invention resides in the combination and arrangement of parts herein 30 after described and claimed, it being understood that changes in the precise embodiment of the invention herein disclosed can be made within the scope of what is claimed without departing from the spirit of the 35 invention.

In the accompanying drawings which illustrate the invention:

Figures 1 and 2 show a diagram of the system.

40 Fig. 3 is a front elevation of a recording voltmeter employed in carrying out the invention.

Fig. 4 is a broken plan view of a third rail.

45 Fig. 5 is a cross section on line V—V of Fig. 4.

Fig. 6 is a vertical section of an air valve and an electromagnet for opening said valve.

50 Referring now to the drawings, A and B designate the main track rails, those on each side of the track being bonded or otherwise connected to each other to conduct an electric current.

55 2 designates a third rail laid in the center

of the track. This third rail 2 has oppositely-disposed, parallel conductors 4 and 5 insulated from each other and divided into blocks of suitable length generally indicated at 8, 9, 10, 11, 12 and 13 and insulated electrically from each other. Each block is arranged alternately with respect to the opposite parallel block. For instance, the ends of block 10 terminate midway between the ends of blocks 9 and 11.

Groups of signal lamps 14 and 15, 16 and 17, 18 and 19, 20 and 21, 22 and 23, are arranged at the ends of the respective blocks as shown on Fig. 1. Said signal lamps may be mounted upon suitable supports along the right of way and may all be placed at one side of the track, or at opposite sides thereof as shown.

When a train or locomotive indicated by the dotted lines 30, comes onto any two blocks, say, for instance, blocks 9 and 10, it completes the following circuit: Starting from alternating generator 32 the current passes through a wire 34, one arm of a double pole switch 35, a wire 36, a recording 80 voltmeter or other suitable meter 38, a wire 40, a lamp 41, mounted in a thermostatic socket having a make-and-break contact, a wire 42, one arm of a double pole, double throw switch 44, a wire 45, a brush or trolley 47 carried by the locomotive and bridging both sides of the third rail 2, block 10, wires 50 and 51 connected, respectively, to the ends of said block 10, lamps 17 and 20, wires 53 and 55, rails A and B, the wheels 90 and axle 58 and 59, respectively, a wire 60, the opposite arm of the switch 44, and back to the generator 32 through a wire 62, the switch 35, and a wire 63.

In addition to the lamps 17 and 20, at the opposite ends of the block 10, being lighted by closing of the foregoing circuit, the lamps 15 and 18 at the ends of the block 9, are also made to glow by current passing through said block 9 from the brush 47, thence 95 through wires 65 and 66, said lamps 15 and 18, wires 68 and 69, the rails A and B, and back through the wheels 58 and the axle 59, to the generator 32 through the intervening conductors above-described.

When the signal lamps of the two blocks are in circuit as described, the recording voltmeter 38 registers, "Safety," while the lamp 41 glows dimly. However, should a rail on either side of the main track be 110

- broken the signal lamp or lamps connected to such broken rail become dark and thus warn the engineer that the track is not in safe condition. Darkness of said signal 5 lamps reduces the current strength passing through the lamp 41, causing it to become dark, or very dim, as an additional warning to the engineer that the track is not in safe condition.
- 10 If two trains, such as indicated at 30 and 30^a, going in the same or opposite directions enter upon the same block, they are automatically stopped before they can collide, by the aid of their air brakes and the throwing 15 of their respective throttles to neutral position. Their whistles are also automatically sounded to notify each engineer of the cause of the trouble. The foregoing is accomplished in the following manner: As 20 the brushes 47 and 47^a of the respective locomotives 30 and 30^a, enter the same block the combined voltage of their alternating generators 32 and 32^a is thrown into such block, causing the lamps 41 and 41^a 25 to pulsate and the voltmeter indicators 72 and 72^a, to intermittently swing into engagement with their respective contacts 74 and 74^a and close air brake circuits on the respective trains, as will now appear.
- 30 As the indicator 72 of the voltmeter 38 momentarily engages its respective contact 74, current passes from the generator 32 through wire 34, one side of switch 35, wire 36, wire 40, a wire 76, indicator 72, contact 74, wire 77, electromagnet 78, a wire 79, a wire 80, wire 62, the opposite side of switch 63, and back to the generator 32 through the wire 63. The foregoing circuit energizes the electromagnet 78, causing 40 it to attract its armature 81 which is pivoted at 82 and fixed to a latch 83, causing the same to release a drop switch 84, which closes an air brake circuit through contacts 85.
- 45 Said air brake circuit derives its energy from the generator 32, and consists of a wire 86 leading from the wire 40, an electromagnet 87, the wire 88, the drop switch 84, contacts 85, a wire 79, the wire 80, the 50 wire 62, one side of the switch 35, and back to the generator 32 through the wire 63. As the electromagnet 87 is energized it opens the air brake valve 89, thereby setting the brakes on the train 30. The brakes 55 on the train 30^a are also set by a similar circuit thereon. In addition to the air brake circuits being energized as above described, the combined energy of the generators 32 and 32^a is thrown into the third rail 2 and 60 the main track rails A and B, through the circuits leading from the generators through the brushes 47 and 47^a and the car wheels and axles of the respective trains.
- Closure of the air brake circuits as above 65 described, also closes a throttle circuit con-

sisting of wires 99 and 100, connected, respectively, to the wires 76 and 82 and the poles of an electromagnet 101, whose armature 102 is connected to an air valve 103 (Fig. 6). The construction of the electromagnet 101 and the air valve 103, is the same as that of the electromagnet 87 and the valve 89. Said air valve 103 has a pipe connection 105 with the air brake system of the train, and upon being opened when the magnet 101 is energized, admits air to a cylinder 107 through a pipe 108. A plunger 109 within the cylinder 107, is forced forward by the air under pressure entering said cylinder from the pipe 108, and pulls the throttle 111 to neutral position. Forward movement of the plunger 109 also actuates a cable 112, connected thereto and the locomotive whistle 110, causing the same to sound.

The foregoing operation of setting the brakes, throwing the throttle to neutral, and operating the whistle on the locomotive 30, simultaneously takes place on the locomotive 30^a, which is similarly equipped as indicated by corresponding numerals with exponents, a portion of such equipment, however, being omitted from the diagram as unnecessary of portrayal since the two equipments are duplicates. The air brake 95 circuits remain closed until interrupted by manually opening the respective drop switches 84 and 84^a.

As the two trains are thus brought to a stop a safe distance apart the engineers on the respective locomotives will naturally want to communicate with each other as to further procedure, and a telephonic circuit has therefore been provided for this purpose. This is accomplished by throwing the 105 switches 44 and 44^a, into engagement with contacts 115, 115^a, on the telephonic circuit and establishing communication between the telephones 117 and 117^a, on the locomotives 30 and 30^a, respectively, through a wire 119, 110 switch 44, wire 45, brush 47, the third rail 2, wire 45^a, switch 44^a, wire 119^a, telephone 117^a, wire 120^a, wire 60^a, switch 44^a, the wheels 58^a, axle 59^a, the track rails A and B, the wheels 58 and axle 59, wire 60, switch 115 44, and a wire 120, leading to the telephone 117 from one of the contacts 115.

I have also provided means whereby a train despatcher at a local station, such as indicated by the dotted lines 125, may enter 120 into telephonic communication with a train approaching or leaving such station. For this purpose the station is equipped with a telephone 130, a signal lamp 131, a double-pole switch 132, and a double-pole, double-throw switch 134. If the train is approaching or leaving the left side of the station 125, the switch 134 is thrown into engagement with contacts 136 to establish the following circuit: Beginning with the generator 125 130

32, the current flows through wire 34, one side of switch 35, wire 36 and the recording voltmeter 38, wire 42, one side of switch 44, wire 45, the block conductor 10, wire 140, 5 one side of switch 134, wire 142, wire 143, lamp 131, wire 145, the opposite side of switch 134, wire 147, the track rail B, wheels 58, axle 59, wire 60, switch 44, wire 62, switch 35, and back to the generator 32 through the 10 wire 63. This circuit causes the station lamp 131 to glow and by opening an additional path for the current passing through the meter 38, it affects the indicator 72 accordingly, and thus warn the engineer that the train 15 dispatcher has orders to deliver over the phone. The engineer may, without stopping the train, then cut in his telephone 117 by throwing the switch 44 into engagement with the contacts 115. This operation cuts 20 the generator 32 out of the telephonic circuit, whereupon the station lamp 131 becomes dark and thus notifies the train dispatcher that the train has reached one of the blocks in which the station is situated, so that he 25 may converse with the engineer. He then cuts out the lamp 131 and cuts in his phone 130, by closing the switch 132.

If the train be approaching the station 125 from the right or passing to the right from 30 such station, the train dispatcher may get in telephonic communication therewith in the manner above described, excepting that the switch 134 is thrown into engagement with contacts 150, one of which communicates with 35 a wire 151 connected to the rail B and the other to a wire 153 connected to one side of the third rail 2. The station telephone wires 140 and 153, are, preferably, connected to two aligned blocks, such as 10 and 12, respectively, 40 to permit ample time for the dispatcher to issue orders of usual length to the engineer, while the train is running in said blocks.

Means whereby the engineer may detect an open switch when approaching the same 45 has been provided as follows:

Referring to Fig. 2, which is a continuation of Fig. 1, it will be observed that the switch points E and F are united by the usual cross bar G, preferably, connected at 50 one end to the crank H of the usual switch stand. Said cross bar G carries a contact 180, connected to one side of the third rail 2 by a wire 181. When the switch is thrown to open position as shown, the contact 180 55 engages a stationary contact 182 connected to the switch rail I by a wire 183. The closing of this circuit cuts out the signal lamps beside the track in circuit with the conductor 5 and causes the indicator 72 of the meter 38 60 to swing toward the contact 74 and register "Danger."

Means have also been provided for indicating an open derail such as indicated at J, by providing the same with a contact 188, 65 electrically connected to one of the main rails

as B by a wire 189. When the derail is thrown open the contact 188 engages a contact 186 on the switch rail I, which contact is connected to one side of the third rail 2 by a wire 187. When the contacts 186 and 188 70 are in engagement as shown, the same action takes place as when the switch is open, that is to say, the signal lamps beside the track go out while the meter 38 registers "Danger."

The recording meter 38 is provided with a 75 clock driven chart 200 divided by lines 201 to indicate the time required for the train to make a trip, and also to indicate the time when the indicator stylus 202 recorded, "Caution," "Danger," etc. The chart 200 is 80 also divided by concentric circles which coact with the indicator 72 in advising the engineer of the condition of the apparatus, the track, etc. For instance, when the stylus 202 is on or adjacent the line 205 it signifies danger ahead. When the stylus is on or adjacent the line 206 it denotes that the engineer should proceed with caution. When the stylus is on or adjacent the line 207 it denotes safety. When the stylus is on or adjacent 85 the line 208 it denotes that the train dispatcher desires to issue orders to the engineer. When the stylus is on the line 209 it signifies that a switch or derail is open, and when the indicator swings into engagement 90 with the contact 74 it indicates that two trains are in the same block. A new chart is provided for each trip.

From the foregoing description it is apparent that I have produced a system embodying the features of advantage above enumerated and one that is well adapted for the purposes intended.

Having thus described my invention, what I claim and desire to secure by Letters Patent, is:

1. In a system of the character described, the combination with a train and a main track therefor, of a third rail having two parallel conductors divided into blocks, the 110 blocks of one conductor being alternately arranged with respect to the blocks of the companion conductor, signals adjacent the main track and having electrical connections therewith and with the blocks of the third 115 rail, a partial circuit on the train having one end in communication with the main track through running gear of the train, a traveling contact on the third rail and connected to the opposite end of said partial 120 circuit, a source of electrical energy for the circuit, and a recording instrument on the train and connected to said circuit.

2. In a system of the character described, the combination with a train and a main 125 track therefor, of a third rail having two parallel conductors divided into blocks, signal lamps adjacent the main track and having electrical connections therewith and with the blocks of the third rail, a partial circuit 130

on the train having one end in communication with the main track, a traveling contact on the third rail and connected to the opposite end of said partial circuit, a source of electrical energy for the circuit, and an indicator on the train and connected to said circuit.

3. In a system of the character described, the combination with a train, a main track therefor, and a derail, of a third rail having two parallel conductors divided into blocks, signals adjacent the main track and having electrical connections with said track and the blocks, a partial circuit on the train having one end in communication with the main track, a traveling contact on the third rail and connected to the opposite end of said partial circuit, a source of electrical energy for the circuit, a recording instrument on the train and connected to said circuit, and means for closing the short circuit between the derail and one of the blocks when said derail is in open position.

4. An electric signaling system for railroad trains, consisting of block conductors electrically connected to the track, a contact on the train to traverse said block conductors, a piston connected to the locomotive throttle to close the same, a cylinder in which said piston is reciprocably mounted, a pipe to conduct fluid under pressure to said cylinder to actuate the piston, a normally closed valve connected to said pipe to control the flow of fluid therethrough, an electromagnet to open said valve, a circuit for energizing said electromagnet, a source of electrical energy connected to said circuit, conductors connecting said source to the contact which traverses the block conductors, a self-closing switch to close the circuit, a latch to normally hold said switch open, and electrically-controlled means to disengage the latch from said switch.

5. An electric signaling system for railroad trains, consisting of block conductors electrically connected to the track, a contact on the train to traverse said block conductors, a piston connected to the locomotive throttle to close the same, a cylinder in which said piston is reciprocably mounted, a pipe to conduct fluid under pressure to said cylinder to actuate the piston, a normally closed valve connected to said pipe to control the flow of fluid therethrough, an electromagnet to open said valve, a circuit for energizing said electromagnet, a source of electrical energy connected to said circuit, conductors connecting said source to the contact which traverses the block conductors, a self-closing switch to close the circuit, a latch to normally hold said switch open, an electromagnet in the circuit to release the latch from said switch, and a meter to close that portion of the circuit leading to said electromagnet to energize the same.

6. An electric signaling system for railroad trains, consisting of block conductors electrically connected to the track, a contact on the train to traverse said block conductors, a piston connected to the locomotive throttle to close the same, a cylinder in which said piston is reciprocably mounted, a pipe to conduct fluid under pressure to said cylinder to actuate the piston, a normally closed valve connected to said pipe to control the flow of fluid therethrough, an electromagnet to open said valve, a circuit for energizing said electromagnet, a source of electrical energy connected to said circuit, conductors connecting said source to the contact which traverses the block conductors, a self-closing switch to close the circuit, a latch to normally hold said switch open, an electromagnet in the circuit to release the latch from said switch, a meter having a vibratory indicator connected to the circuit, and a contact adapted to be engaged by said indicator and close that portion of the circuit leading to said electromagnet to energize the same.

7. An electric signaling system for railroad trains, consisting of block conductors electrically connected to the track, a contact on the train to traverse said block conductors, a piston connected to the locomotive throttle to close the same, a cylinder in which said piston is reciprocably mounted, a pipe to conduct fluid under pressure to said cylinder to actuate the piston, a normally closed valve connected to said pipe to control the flow of fluid therethrough, an electromagnet to open said valve, a circuit for energizing said electromagnet, a source of electrical energy connected to said circuit, conductors connecting said source to the contact which traverses the block conductors, a self-closing switch to close the circuit, a latch to normally hold said switch open, an electromagnet in the circuit to release the latch from said switch, a meter having a vibratory indicator connected to the circuit, a contact adapted to be engaged by said indicator and close that portion of the circuit leading to said electromagnet to energize the same, and a clock-driven record over which said indicator swings.

8. An electric signaling system for railroad trains, consisting of block conductors electrically connected to the track, a contact on the train to traverse said block conductors, a piston connected to the locomotive throttle to close the same, a cylinder in which said piston is reciprocably mounted, a pipe to conduct fluid under pressure to said cylinder to actuate the piston, a normally closed valve connected to said pipe to control the flow of fluid therethrough, an electromagnet to open said valve, a circuit for energizing said electromagnet, a source of electrical energy connected to said circuit,

- conductors connecting said source to the contact which traverses the block conductors, a self-closing switch to close the circuit, a latch to normally hold said switch open, an electromagnet in the circuit to release the latch from said switch, a meter having a vibratory indicator connected to the circuit, a contact adapted to be engaged by said indicator and close that portion of the circuit leading to 5 said electromagnet to energize the same, a stylus carried by the indicator, and a clock-driven record engaged by said stylus.
9. An electric signaling system for railroad trains, consisting of block conductors 15 electrically connected to the track, a contact on the train to traverse said block conductors, a piston connected to the locomotive throttle to close the same, means oper- 20 ably connecting the piston to the locomotive whistle, a cylinder in which said piston is reciprocably mounted, a pipe to conduct fluid under pressure to said cylinder to actuate the piston, a normally closed valve connected to said pipe to control the flow of 25 fluid therethrough, an electromagnet to open said valve, a circuit for energizing said electromagnet, a source of electrical energy connected to said circuit, conductors connecting said source to the contact which traverses 30 the block conductors, a self-closing switch to close the circuit, a latch to normally hold said switch open, and electrically-controlled means to disengage the latch from said switch.
- 35 10. An electric signaling system for railroad trains, consisting of block conductors electrically connected to the track, a contact on the train to traverse said block conductors, a brake-applying valve, an electromagnet to open said valve, a circuit for energizing said electromagnet, a source of electrical energy connected to said circuit, conductors connecting said source to the contact which traverses the block conductors, a self-closing switch to close the circuit, a latch to normally hold said switch open, and electrically-controlled means to disengage the latch from the switch.
- 40 11. An electric signaling system for railroad trains, consisting of block conductors electrically connected to the track, a contact on the train to traverse said block conductors, a brake-applying valve, an electromagnet to open said valve, a circuit for energizing said electromagnet, a source of electrical energy connected to said circuit, conductors connecting said source to the contact which traverses the block conductors, a self-closing switch to close the circuit, a latch to normally hold said switch open, and electrically-controlled means to disengage the latch from the switch.
- 45 12. An electric signaling system for railroad trains, consisting of block conductors electrically connected to the track, a contact on the train to traverse said block conductors, a brake-applying valve, an electromagnet to open said valve, a circuit for energizing said electromagnet, a source of electrical energy connected to said circuit, conductors connecting said source to the contact which traverses the block conductors, a self-closing switch to close the circuit, a latch to normally hold said switch open, electrically-controlled means to disengage the latch from the switch, and a meter to open and close the circuit to said electrically controlled means.
- 50 13. An electric signaling system for railroad trains consisting of block conductors electrically connected to the track, a contact on the train to traverse said block conductors, a brake-applying valve, an electromagnet to open said valve, a circuit for energizing said electromagnet, a source of electrical energy connected to said circuit, conductors connecting said source to the contact which traverses the block conductors, a self-closing switch to close the circuit, a latch to normally hold said switch open, electrically-controlled means to disengage the latch from the switch, a meter in the circuit and provided with an indicator and a contact adapted to be engaged by said indicator and close that portion of the circuit leading to 55 said electrically controlled means, and a clock-driven record over which said indicator swings.
- 55 14. An electric signaling system for railroad trains, consisting of block conductors electrically connected to the track, a contact on the train to traverse said block conductors, a brake-applying valve, an electromagnet to open said valve, a circuit for energizing said electromagnet, a source of electrical energy connected to said circuit, conductors connecting said source to the contact which traverses the block conductors, a self-closing switch to close the circuit, a latch to normally hold said switch open, electrically-controlled means to disengage the latch from the switch, a meter in the circuit and provided with an indicator, a contact adapted to be engaged by said indicator and close that portion of the circuit leading to 60 said electrically controlled means, a stylus carried by the indicator, and a clock-driven record engaged by said stylus.
- 60 15. An electric signaling system for railroad trains, consisting of block conductors electrically connected to the track, a contact on the train to traverse said block conductors, a piston connected to the locomotive throttle to close the same, a cylinder in which said piston is reciprocably mounted, an alternat-
- 70 75 80 85 90 95 100 105 110 115 120 125 130

ing generator, conductors connecting said generator to the circuit and the block conductors, a drop-switch to close the circuit, mechanical means to normally hold said switch open, and electrically-controlled means to disengage said mechanical means from the switch.

16. An electric signaling system for railroad trains, consisting of block conductors 10 electrically connected to the track, a contact on the train to traverse said block conductors, a piston connected to the locomotive throttle to close the same, a cylinder in which said piston is reciprocably mounted, an alternating generator, conductors connecting said generator to the circuit and the block conductors, a drop-switch to close the circuit, mechanical means to normally hold said switch open, electrically-controlled means to 20 disengage said mechanical means from the switch, a meter having a vibratory indicator connected to the circuit, a contact adapted to be engaged by said indicator and close that portion of the circuit leading to said electromagnet to energize the same, a clock-driven record over which said indicator swings, and a stylus carried by said indicator to engage the clock-driven record.

17. An electric signaling system for railroad trains, consisting of block conductors 30 electrically connected to the track, signal lamps beside the track and connected thereto and to said block conductors, a contact on the train to traverse said block conductors, a piston connected to the locomotive throttle to close the same, a cylinder in which said piston is reciprocably mounted, a pipe to conduct fluid under pressure to said cylinder to actuate the piston, a normally closed valve 40 connected to said pipe to control the flow of fluid therethrough, an electromagnet to open said valve, a circuit for energizing said electromagnet, a source of electrical energy connected to said circuit, conductors connecting 45 said source to the contact which traverses the block conductors, a self-closing switch to close the circuit, a latch to normally hold said switch open, and electrically-controlled means to disengage the latch from said 50 switch.

18. An electric signaling system for railroad trains, consisting of block conductors 55 electrically connected to the track, contacts on two trains to traverse said block conductors, partial circuits on the trains and connected to said contacts and the running gear of the trains, alternating generators on the trains and connected to the partial circuits, meters on the trains and connected to the partial 60 circuits, indicators on the meters and connected to the partial circuits, records on the meters over which said indicators swing, contacts adapted to be engaged by the indicators, electromagnets connected to the partial 65 circuits and the last-mentioned contacts,

switches controlled by said electromagnets, and air-brake circuits on the trains controlled by said switches.

19. An electric signaling system for railroad trains, consisting of block conductors 70 electrically connected to the track, contacts on two trains to traverse said block conductors, partial circuits on the trains and connected to said contacts and the running gear of the trains, alternating generators on the 75 trains and connected to the partial circuits, voltmeters on the trains and connected to the partial circuits, indicators on the voltmeters and connected to the partial circuits, records on the voltmeters over which said indicators 80 swing, contacts adapted to be engaged by the indicators, electromagnets connected to the partial circuits and the last-mentioned contacts, switches controlled by said electromagnets, air-brake circuits on the trains controlled by said switches, and signal lamps on the trains having thermostatic sockets connected to the partial circuits.

20. An electric signaling system for railroad trains, consisting of block conductors 90 electrically connected to the track, contacts on two trains to traverse said block conductors, partial circuits on the trains and connected to said contacts and the running gear of the trains, alternating generators on the 95 trains and connected to the partial circuits, meters on the trains and connected to the partial circuits, indicators on the meters and connected to the partial circuits, records on the meters over which said indicators swing, 100 contacts adapted to be engaged by the indicators, electro-magnets connected to the partial circuits and the last-mentioned contacts, switches controlled by said electromagnets, and steam shutting-off circuits on the trains 105 controlled by said switches.

21. An electric signaling system for railroad trains, consisting of block conductors connected to the track, a contact on the train to traverse said block conductors, a 110 partial circuit on the train and connected to said contact and the running gear of the train, a source of electrical energy on the train and connected to the partial circuit, a manual switch to open and close the partial 115 circuit, a meter connected to the partial circuit, a clock-driven record on the meter, and an indicator in circuit with the partial circuit and arranged to swing over said record.

22. An electric signaling system for railroad trains, consisting of block conductors connected to the track, a contact on the train to traverse said block conductors, a partial circuit on the train and connected to said contact and the running gear of the train, a source of electrical energy on the train and connected to the partial circuit, a meter connected to the partial circuit, a clock driven record on the meter, an indicator in circuit with the partial circuit and 130

- arranged to swing over said record, and a stylus carried by the indicator to inscribe upon the record.
23. An electric signaling system for rail-road trains, consisting of block conductors connected to the track, a contact on the train to traverse said block conductors, a partial circuit on the train and connected to said contact and the running gear of the train, a source of electrical energy on the train and connected to the partial circuit, a meter connected to the partial circuit, a clock-driven record on the meter, an indicator in circuit with the partial circuit and arranged to swing over said record, and air-brake circuit connected to the partial circuit, and a contact connected to the air-brake circuit to close the same when said contact is engaged by the indicator.
24. In a system of the character described, the combination with a train, a main track therefor, and a local station, of a sectional third rail electrically connected to said track, a partial circuit on the train having one end in communication with the main
- track, a traveling contact on the third rail and connected to the opposite end of said partial circuit, a source of electrical energy for the circuit, a telephone on the train, a double-pole double-throw switch for cutting out that portion of the partial circuit on the train containing the source of electrical energy and cutting in the telephone with the remainder of such partial circuit, a telephone in the local station, conductors to establish communication between the last-mentioned telephone, the track and two sections of the third rail, a double-pole double-throw switch for cutting said conductors in circuit with either section of the third rail, conductors connecting the last-mentioned switches to the station telephone, and a switch for opening and closing the last-mentioned conductors.
25. In testimony whereof I affix my signature, in the presence of two witnesses.

WILLIAM H. ADKINS.
